UNITED STATES PATENT OFFICE.

EDWARD M. HALL AND FRANK PEARSE, OF DEXTER, NEW YORK.

PULP-SCREEN.

SPECIFICATION forming part of Letters Patent No. 521,409, dated June 12, 1894.

Application filed January 11, 1894. Serial No. 496,529. (No model.)

To all whom it may concern:

Be it known that we, EDWARD M. HALL and FRANK PEARSE, citizens of the United States of America, residing at Dexter, in the county 5 of Jefferson and State of New York, have invented certain new and useful Improvements in Pulp-Screens; and we do hereby declare the following to be a full, clear, and exact description of the invention, such as will enable others skilled in the art to which it appertains to make and use the same, reference being had to the accompanying drawings, and to letters of reference marked thereon, which form a part of this specification.

15 This invention relates to improvements in pulp-screens; and it consists in providing the diaphragm of a pulp-screen with springs which are adapted to move said diaphragm against the action of the cams on the operating shaft, the springs extending across the diaphragm so as to bear upon the side pieces of the frame of the pulp-screen.

20 In the accompanying drawings, forming part of this specification, Figure 1 is a side view of a pulp-screen, partly in section, showing our improvements applied thereto. Fig. 2 is a sectional view on the line 2—2 of Fig. 1, and Fig. 3 is a detail plan view, a part of the screen-plate being broken away.

25 A designates the base of the pulp-screen, the frame B of which is provided with a suitable trough B' and with a series of transverse beams B² which form supports for the diaphragm on each side of the compartments of the pulp-chamber. Upon the frame B is secured the diaphragm D, which is of suitable flexible material, and across this diaphragm between the transverse beams B² are located springs E, and upon these springs are attached 30 plates e against which the cams c on the operating shaft C bear. On the under side of the diaphragm beneath the springs are attached reinforcing strips e'. The springs E and reinforcing strips e and e' are connected to the 35 diaphragm by bolts or rivets e².

40 F designates the upper frame of the pulp-screen to the side pieces of which are attached transverse partitions F' which divide the pulp-chamber G into a series of compartments 45 g; these partitions lie immediately above the transverse beams B² and through the same passes the operating shaft C. The inner sides

of the frame F are provided with ledges to which is secured a perforated screen-plate H, said plate also resting upon the upper edges 55 of the partitions F'. The end pieces of the frame F are provided with bearings f for the operating shaft C. The shaft is provided in each compartment of the pulp-chamber with a cam c, which when the shaft is turned 60 is adapted to engage with the plates or strips e so as to vibrate the diaphragms. The frame F is connected to the frame B in any suitable manner, preferably by bolts so that the parts can be securely connected together. 65

Each compartment of the pulp-chamber has an outlet opening g' which communicates with the trough B'.

In operation the pulp is fed into the pulp screen above the perforated screen-plate H 70 and the shaft is driven so as to vibrate the diaphragms which will cause the pulp to be drawn through the perforated screen-plate into the compartments of the pulp-chamber and it then finds its way to the trough B' from 75 which it may be conveyed to a suitable discharge pipe.

It will be noted that the diaphragms are partially supported by the springs, and that they are alternately vibrated, the cams being in 80 different positions upon the shaft.

A pulp-screen constructed as herein shown and described may be set up to occupy but little space, and in operation will agitate the pulp above the screen-plate so as to render the 85 straining positive and effective.

We are aware that prior to our invention it has been proposed to provide a paper pulp-screen with a straining plate below which is located a diaphragm, said diaphragm being 90c adapted to be vibrated by a shaft having cam-disks, and we do not claim such construction broadly; but

What we do claim as new, and desire to secure by Letters Patent, is—

1. In a pulp-screen, the combination, with a base having a diaphragm and transverse springs connected thereto, of a shaft having cams for vibrating the diaphragms, the shaft and cams carried thereby being within the 100 pulp-chamber, substantially as described and for the purpose set forth.

2. In a pulp-screen constructed substantially as described, the combination, of the dia-

phragms having springs and bearing-plates attached above said springs, of a shaft mounted above the diaphragms and below the screen-plate, said shaft having cams which are 5 adapted to bear upon the bearing-plates, substantially as described and for the purpose set forth.

3. In a pulp-screen, the combination, of a base constructed substantially as described 10 and provided with transverse beams B², dia- phragms connected to said base and provided with springs, bearing-plates e attached to the springs and reinforcing strips e' attached on

the under side of the diaphragms and beneath the springs, a shaft having cams mounted 15 thereon, and a screen-plate secured to the box and adapted to rest upon the partitions F' thereof, substantially as shown and for the purpose set forth.

In testimony whereof we affix our signatures 20 in presence of two witnesses.

EDWARD M. HALL.
FRANK PEARSE.
